CLAIM

The ornamental design for a shoe with replaceable sole, as shown and described.

DESCRIPTION

FIG. 1 is a front and top perspective view of a shoe with replaceable sole, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in an alternative position; and,

FIG. 10 is an enlarged view of a portion indicated with numeric 10 in FIG. 2.

The dash dot dash lines in FIGS. 2 and 10 are for the purpose of depicting the cut line of the enlarged view and form no part of the claim. The broken lines in the figures illustrate portions of the shoe with replaceable sole that form no part of the claimed design.
